UNITED STATES PATENT OFFICE.

HARRY A. HIGGINS, OF DETROIT, MICHIGAN, ASSIGNOR TO DIAMOND POWER SPECIALTY COMPANY, OF DETROIT, MICHIGAN, A COPARTNERSHIP.

BLOWER FOR WATER-TUBE BOILERS.

1,101,545.

Specification of Letters Patent. Patented June 30, 1914.

Application filed March 11, 1911. Serial No. 613,680.

To all whom it may concern:

Be it known that I, HARRY A. HIGGINS, a citizen of the United States of America, residing at Detroit, in the county of Wayne and State of Michigan, have invented certain new and useful Improvements in Blowers for Water-Tube Boilers, of which the following is a specification, reference being had therein to the accompanying drawings.

This invention relates to boiler-flue cleaners, and particularly to that class thereof which may be applied to the setting of what is generally known as the "inclined water tube" boiler, and it has for one of its objects the provision of such an apparatus which may be projected into, and withdrawn out of, the boiler setting, through the side wall thereof.

The invention has, furthermore, for its object the provision of means whereby each individual blower pipe may be manipulated to move in the arc of a plane in parallelism with the boiler tubes.

Further objects of the invention will hereinafter appear and be particularly defined in the claims.

The invention has been clearly illustrated in the accompanying drawings, in which similar characters denote similar parts, and in which—

Figure 1 is a fractional side view of a boiler-setting having my improved flue-blower attached thereto; Fig. 2 is a horizontal section thereof; Figs. 3 and 4 illustrate in horizontal and vertical sections, respectively, one of the blower heads carried by the ends of the blower-tubes; Figs. 5 and 6 are views similar to Figs. 1 and 2, but represent a modification of the apparatus; and Fig. 7 illustrates in perspective view, the means preferably employed for manipulating the flue cleaners as per modification, simultaneously.

Briefly stated, the present invention comprises a series of superposed steam-supplying or blower-tubes each carrying at its inner end a distributing head which may be swung in an inclined plane corresponding to the inclination of the boiler-tubes so as to clean off all soot, dust, ashes, etc., which may have lodged on top of the several tubes. The blower tubes receive their steam-supply from a vertical stand-pipe which may be bodily swung toward and away from the

wall, and which, itself, may be oscillated in its supporting hangers so as to cause the tube-heads to describe a small arc over the boiler-tubes. Furthermore, each head has a series of nozzles which are successively brought into steam-blowing operation by a valve rotatable in the head, and all of these valves may be operated simultaneously.

Referring to the hangers, the steam boiler is in the present instance of the "inclined water-tubes" variety and comprises the tubes 10 in which the water is heated by the products of combustion passing through the spaces between the tubes in a boiler setting comprising a side-wall 11 which has the usual side openings 12 in a plate 13 set into the wall, said opening being normally closed by gates (not shown) but adapted to be opened to permit the insertion of cleaning tools.

In the preferred form thereof shown, my improved flue-blower comprises a steam-supply pipe 15 having a horizontal branch 16 provided with a valve 17 and an elbow 18 which latter constitutes a journal-support 20 for a vertical nipple 19 in communication with a swing-pipe 20, the outer elbow 21 of which pivotally supports a vertical pipe 22 to which the several blower-tubes are secured. The nipple 19 has vertical rod-extension 23 the upper end of which is journaled in a bracket 24 secured to the wall 11, and a swing-arm 25 is secured to the rod 23 and pivotally supports at its free end the upper end of the vertical pipe 22 above mentioned, so that in this manner the latter is mounted for revolution around the pivot axis of the rod 23, while the pipe 22 is also pivotally supported in its swinging supports. Secured to and in communication with the pipe 22, are series of blower tubes 26 each of which carries at its end a distributor-head 27, illustrated in detail in Figs. 3 and 4, and comprising a chambered casing 28, the interior of which communicates with a series of apertures or perforations 29, all of which are disposed in the same plane, as shown in Fig. 4. The perforations are so arranged in regard to their directions, that the steam jets issuing therefrom will cover substantially the entire area over the water-tubes of the boiler, but in order to assure a thorough cleansing thereof, the pipe 26 is pivoted in its support so that, therefore, it may be

swung slightly from side to side as limited 110

by the lateral size of the plate-apertures 12, it being understood that, furthermore, the head 27 is of such size as to permit its withdrawal through these apertures. Now, inasmuch as the boiler-tubes are inclined, the heads of the several blower tubes are so arranged that the steam-jets will blow over the tubes in a plane which is parallel to the circulation of the boiler-tubes and thus have a 10 farther-reaching effect than they would have otherwise.

Considering the fact that the provision of a comparatively large number of perforations in each head, multiplied again by 15 the number of such heads, will in a measure open an aggregate outlet for the steam, that its effective pressure and velocity will have a tendency to drop, means are provided for controlling the passage of steam through 20 the perforations by shutting-off some of these jets while others are active, the device for accomplishing this result being such that the several perforations will be successively cut-in and again shut-off. Hence I provide 25 a valve consisting substantially of a hollow cylindrical body 30 having a peripheral helical slot 31 cut in such a manner that, in the instance shown, the rotation of the body, will put the interior of the casing into 30 communication with the perforations, one at a time, although the slot may be wide enough that two or even more may be thus connected. It is also to be understood that 35 for the purposes indicated, a similar groove instead of a slot will answer as well, or the slot may be continued for the entire length of the body, as indicated in dotted lines *a* in Fig. 3, in which case the body becomes self-packing in the chamber 28. The rear 40 end of the body 30 has a strap-ear 32 secured to one end of a rod 33 which extends through the entire length of steam-tube 26, and carries at its outer end a gear 34 (see 45 Figs. 1 and 2) in engagement with similar gears on the several valve rods above and below the same, so that, when one rod is rotated, as for instance by a hand wheel 33', all the rods will be rotated simultaneously, in alternately reverse directions. 50 This hand wheel also affording means for guiding and controlling the swinging movement of the jet-tube and its head into and out of the confines of the setting-walls, as well as shifting it around between the 55 boiler-tubes.

In Figs. 5 to 7 inclusive, I have illustrated a modification of the manipulating means, the principle of the blower remaining the same, that is as far as its hanging-support 60 and its movement *per se* is concerned. In this instance the distributor pipe 22 has short branches 35 which support vertical drop-pipes 36 slightly inclined so as to be substantially at right angles with the axes 65 of the boiler-tubes. Horizontal jet pipes 37

having perforated heads 38, are connected with the drop-pipes 36, the entire organization being such that the jet pipe may be swung about the axis of the drop-pipe 36 in a plane in a parallelism with the inclination of the boiler tubes instead of a horizontal plane about the vertical axis of the distributor pipe first described. In this instance a valve may be employed, as before. Likewise each jet pipe may be rendered independently operable as for example by a 70 rod 38 (see Fig. 6), but I prefer to swing all the jet pipes simultaneously, a mechanism for such function being shown in Fig. 7, in which each drop-pipe carries an arm 40 whereby the jet pipes may be swung around the axis of the drop-pipe 36. Each arm may be oscillated through a link 41, from a crank 42 secured to a vertical shaft or rod 43 which is journaled in bearing-lugs 44 secured to the vertical distributing pipe 45. The latter is hung for swinging movement in the same manner as the pipe 22 above described.

Attention is called to the fact that the head occupies a tilted position so as to bring the jet-perforations into a plane parallel with the inclination of the boiler tubes.

Many changes may be made in the construction and general organization of the elements, without departing from the spirit of the invention.

I claim:

1. The combination with the side-wall of a boiler setting having perforations therein, of a blower comprising a series of jet-tubes adapted to pass through said perforations, a pipe connecting the outer ends of said tubes, means for pivotally supporting said pipe for swinging movement relatively to said wall, and a steam-supply connected with said pipe.

2. The combination with the side-wall of a boiler setting having perforations therein, of a blower comprising a series of jet-tubes adapted to pass through said perforations, a pipe connecting the outer ends of said tubes, means for pivotally supporting said pipe on said wall, comprising a horizontal swing-pipe connected therewith, and a swing arm at the other end of said connector pipe and a steam-supply connected with said pipe, and means for swinging each tube longitudinally of the boiler-tubes.

3. The combination with the side-wall of a boiler setting having vertically aligned perforations therein, of a blower comprising a series of superposed jet-tubes adapted to pass through said perforations, a vertical pipe connecting the outer ends of said tubes, means for pivotally supporting said pipe for swinging movement relatively to said wall, and a steam-supply connected with said pipe, and means for controlling the passage of steam through said jet tubes.

4. The combination with the side-wall of

a boiler setting having vertically alined perforations therein, of a blower comprising a series of jet-tubes adapted to pass through said perforations, a vertical pipe connecting the outer ends of said tubes, means for pivotally supporting the said pipe for swinging movement relatively to said wall, a steam-supply connected with said pipe, and means for swinging the jet tubes in a plane parallel with the boiler tubes.

5 5. A blower for boiler-tubes comprising a series of jet tubes, a steam pipe connecting the outer ends of the said tubes, a head carried by the free end of each jet tube and having a series of differently-directed perforations, and means for controlling the passage of steam through said perforations.

20 6. A blower for boiler-tubes comprising a series of jet tubes, a steam pipe connecting the outer ends of said tubes, a head carried by the free end of each jet tube and having a series of differently-directed perforations, and means for successively opening and closing said perforations.

25 7. A blower for boiler-tubes comprising a series of jet tubes, a steam pipe connecting the outer ends of said tubes, a head carried by the free end of each jet tube and having a series of separate alined perforations, and

a rotatable plug in each head for successively opening and closing said perforations.

8. A blower for boiler-tubes comprising a series of jet tubes, a steam pipe connecting the outer ends of said tubes, a head carried by the free end of each jet tube and having a series of separate perforations, and a rotatable plug in each head for successively opening and closing said perforations, and means for actuating said plugs simultaneously.

9. The combination with the side wall of a boiler setting having alined superposed perforations, of a blower comprising a vertical stand-pipe, adapted for swinging movement toward and away from said wall, and having a series of superposed alined branches, a series of jet-tubes pivoted on said branches on axes substantially at right angles with the axes of the boiler tubes, means for swinging said tubes on the branches, and a steam-supply connected with the stand-pipe.

In testimony whereof I affix my signature in presence of two witnesses.

HARRY A. HIGGINS.
